UNITED STATES PATENT OFFICE.

FRANK M. PIERCE, OF CHICAGO, ILLINOIS.

AUTOMATICALLY-ADJUSTABLE TENSIONING DEVICE.

1,399,988.

Specification of Letters Patent. Patented Dec. 13, 1921.

Application filed April 29, 1920. Serial No. 377,533.

To all whom it may concern:

Be it known that I, FRANK M. PIERCE, a citizen of the United States, and a resident of the city of Chicago, in the county of Cook and State of Illinois, have invented certain new and useful Improvements in an Automatically-Adjustable Tensioning Device; and I do hereby declare that the following is a full, clear, and exact description 10 of the same, reference being had to the accompanying drawings, and to the numerals of reference marked thereon, which form a part of this specification.

This invention relates to an automatically 15 adjustable tensioning device which is particularly adapted for use in wrapping and unwrapping machines. In commercial wrapping and unwrapping machines the strip of investing material is usually wound on a 20 positively driven reel. In order to prevent tearing of the strip of investing material and to insure uniform tension on the strip, it is necessary that a friction drive be provided for said rotatable unwinding reel. 25 Since the tension on the investing strip necessarily varies with variations in the size of the roll of flexible material, it is highly desirable that means be provided for automatically adjusting the friction drive of the 30 reel to such varying tensions.

It is an important object, therefore, of this invention to provide a frictionally driven winding reel having means associated therewith whereby said friction drive is 35 automatically adjusted to accommodate varying sizes of a roll of material wound on the reel.

It is also an important object of this invention to provide a reel adapted to have 40 a spool for winding material removably secured thereon and having a friction drive which is automatically adjusted for varying tensions on the strip of material on the reel.

45 Other and further important objects of this invention will be apparent from the disclosures in the specification and drawings.

The invention (in a preferred form) is illustrated in the drawings and hereinafter 50 more fully described.

On the drawings:

Figure 1 is a front elevation of a rotatable tire-unwrapping machine shuttle equipped with the improved reel of this invention.

55 Fig. 2 is a section on the line 2-2 of Fig. 1.

Fig. 3 is a section on the line 3-3 of Fig. 1.

Fig. 4 is an end elevation of the reel.

Fig. 5 is a fragmentary detail partly in 60 section showing the control mechanism for the automatic adjusting mechanism.

Fig. 6 is a section on the line 6-6 of Fig. 3.

Fig. 7 is a section on the line 7-7 of 65 Fig. 3.

Fig. 8 is a section on the line 8-8 of Fig. 3.

As shown on the drawings:

The reel of this invention is rotatably 70 mounted on the face plate 1 of the incomplete annular shuttle which is rotatably supported on the incomplete annular frame 2. Such frame 2 is provided with a horizontal flange 3 as shown in Fig. 2 and said horizontal flange is provided at its outer edge with a vertically projecting rim 4. Flanged supporting rollers 5 which are engaged over said vertical projecting rim 4 are mounted on shafts 6 which are journaled between the 80 face plate 1 and the back plate 7, which is rotatably engaged around the horizontal flange 3. Said flanged supporting rollers 5 are driven by belt 8 which in turn is driven from the flanged pulleys 9 and 10 mounted 85 on the drive shafts 11 and 12. Said belt 8 is engaged over idler pulleys 13 and 14 which are supported on said frame 2.

To provide means for tensioning the belt 8 the idler pulley 14 is mounted on the outer 90 end of the lever 15 which is pivotally supported on the frame 2 at 16 and the inner end of which is engaged around a threaded rod 17. Engaged on the upper end of said threaded rod 17 is a nut 18 and between 95 the inner end of the lever 15 and said nut 18 is a coiled spring 19 engaged around said rod 17 and the tension on said belt 8 may be adjusted by longitudinally adjusting the nut 18 on the threaded rod 17.

An extension shaft 19 is formed on one of the shafts 6, and the winding reel 20 is rotatably mounted on said extension 19. Said reel 20 is provided on its inner end with an integral circular plate 21 which is 105 adapted to engage the floating friction disk 22 on the face of a circular plate 23 which is slidably but non-rotatably mounted on the extension shaft 19 adjacent and inside said plate 21.

110 Means are provided for longitudinally adjusting the winding reel 20 on the extension

shaft 19. A recess is provided in the outer ends of said reel 20 and ball bearings 24 are engaged therein. Engaged on a threaded outer end of the extension shaft 19 is an 5 internally threaded sleeve 25 which is slidable in the recess in the end of the reel 20. Fixed between the ball bearings 24 and the outer end of the sleeve 25 is a coil spring 26 which provides a resilient connection be- 10 tween the sleeve 25 and the winding reel 20. For securing said sleeve 25 in adjusted position a locking plate 27 is provided, said locking plate being engaged over the squared shank of the set screw 28 in the end of the 15 shaft extension 19 and having a cut-out portion 30 in which the pin 29 in the end of the sleeve 25 is slidable.

A boss 31 on the reel 19 provides for removably securing a spool 46 for receiving 20 the unwinding material on said reel.

To insure positive rotation of the extension shaft 19 at all times the shaft 6 on which said extension shaft is mounted and all of the other shafts 6 are each provided 25 with a sprocket wheel as shown in Fig. 3, and said sprocket wheels are interconnected by sprocket chain 33 engaged thereover. A ball bearing 34 is slidably mounted in the shaft 19 and adapted to be engaged in a recess on the inner face of the friction plate 23. Means are provided for varying the pressure exerted on said ball bearing 34 and consequently varying the degree of frictional engagement of the plates 21 and 23. 30

35 For this purpose a forked lever 35 is pivoted on a rounded pin 36 which is secured in the plate 1 and engaged in a recess in the inner side of said lever 35 intermediate the ends thereof. The forked portion of 40 said lever 35 is engaged around the extension shaft 19 adjacent the ball bearings 34 and is provided with pins 37 which are adapted to be engaged against the inner plate of said ball bearing. The opposite end 45 of lever 35 is loosely engaged around a stub shaft 38 which is removably secured in the plate 1. A coil spring 39 is engaged around said stub shaft 38 between the lever 35 and the plate 1 acting normally to hold the lower 50 end of said lever outwardly, and the forked end thereof away from the ball bearing 34. Rotatably engaged on the stub shaft 38 outside of the lever 35 is a sleeve 40 which has a projecting arm 41 secured therein, said projecting arm being provided with an 55 integral extension 42 which is adapted to engage the outside of a roll of material which is being wound on the reel 19. A set screw 43 engaged in the outer end of the 60 stub shaft 38 secures sleeve 40 thereon. In order that rotation of the sleeve 40 will act to rock the lever 35, a cam recess 44 is provided in the inner end of said sleeve, and a pin 45 on the outer end of said lever 45 is 65 engaged in said recess. Consequently, a ro-

tation of the sleeve 40 by the arm 41—42 will cause the cam recess 44 to engage the pin 45 and rock the upper end of the lever 35 inwardly or outwardly on the pivot 36 with or against the action of the coil spring 70 39. The rocking of the lever 35 is of course transmitted to the plate 23 through the pins 37 and the ball bearing 34, thus varying the pressure between the plates 21 and 23.

A guide pin 45 is secured on the face plate 75 1 of the shuttle, as clearly shown in Fig. 1, and said guide pin acts to align the strip of material when it is being unwrapped and wound onto the spool 46 on the reel 19.

The operation is as follows:

The object to be unwrapped is rotated through the shuttle in a plane substantially perpendicular to the plane thereof. The end of the strip of material to be unwrapped is engaged around the guide pin 45 and secured on the spool 46 on the reel 20. The relative rotations of the tire and shuttle will cause the material to be unwrapped from the object and since the reel 20 and the spool 46 are positively rotated, said unwrapped 90 material will be wound on the spool.

As the size of the roll of material on the spool increases, the arm 41—42 is forced outwardly, and the sleeve 40 is consequently rotated, and the resulting engagement of 95 the cam recess 44 with the rounded pin 45 on the lever 35 rocks the upper end of said lever inwardly about the pivot 36, whereby the plate 23 engages the plate 21 with increased pressure, thus compensating for the 100 increased tension on the strip of material being unwrapped due to the increasing size of the roll of material on the spool 46.

It will be readily seen that the above described construction provides an automatic 105 adjustment of the frictional engagement of the plates 21 and 23 in accordance with the varying tension exerted on the strip of material being unwrapped due to the increasing size of the roll of material on the spool. 110

The above process is substantially reversed during the process of wrapping an object, in which case the resistance of the friction mechanism to the tension on the strip of material being wrapped is automatically adjusted in accordance with variations in the size of the roll of material on the shuttle.

It is, of course, obvious that during the wrapping operation, the tension on the strip 120 of material itself will act to rotate the reel, the speed with which it is permitted to rotate being controlled by the automatic mechanism of this invention.

I am aware that numerous details of construction may be varied through a wide range without departing from the principles of this invention, and I therefore do not purpose limiting the patent granted otherwise than necessitated by the prior art.

I claim as my invention:

1. A winding device comprising a shaft, a reel rotatably mounted thereon, a friction plate on the reel, a friction plate slidably but non-rotatable on the shaft adapted to engage said first friction plate, cam-controlled means for varying the frictional engagement of said plates, and a lever for automatically operating said cam controlled means.
2. A winding device comprising a shaft, a reel rotatably mounted thereon and adjustable longitudinally thereof, a friction plate on the reel, a friction plate slidably but non-rotatable on the shaft and adapted to engage said first friction plate, cam-controlled means for varying the frictional engagement of the plates, and pivoted means for automatically operating said cam controlled means.
3. A winding device comprising a shaft, a reel rotatably mounted thereon, a friction plate on the reel, a friction plate slidably but non-rotatably mounted on the shaft and adapted to engage said first friction plate, a pivoted lever for moving the second plate longitudinally on the shaft, and a cam for controlling said pivoted lever.
4. A winding device comprising a shaft, a reel rotatably mounted thereon, a friction plate on the reel, a friction plate slidably but non-rotatable on the shaft and adapted to engage said first friction plate, a spring-pressed lever for adjusting the second plate longitudinally on the shaft, and cam-operated means for moving the lever against the action of the spring.
5. A winding device comprising a shaft, a reel rotatably mounted thereon, means resiliently engaging the outer end of the reel for securing said reel on the shaft and adjusting it longitudinally thereof, a friction plate on the reel, a friction plate slidably but non-rotatable on the shaft to engage said first friction plate, and means for varying the frictional engagement of said plates.
6. A winding device comprising a shaft, a reel rotatably mounted thereon, a friction plate on the reel, a friction plate slidably but non-rotatable on the shaft and adapted to engage said first friction plate, a ball bearing engaging said second friction plate, and means engaging the ball bearing for automatically varying the frictional engagement of the plate.
7. A device of the class described comprising a rotatable reel, frictional means for controlling the rotation thereof, a pivoted lever for adjusting said frictional means, and a movable cam for operating said pivoted lever.
8. A winding device of the class described comprising a shaft, a reel on said shaft, and frictionally driven therefrom, and cam-controlled means separate from the shaft for automatically adjusting the friction drive for the reel in accordance with the size of a roll of material on the reel.
9. A winding device comprising a shaft, a reel rotatable thereon, adjusting means for securing the reel on the shaft, resilient means between said adjusting means and the reel, a friction drive for the reel, and means for automatically adjusting said friction drive.
10. A device of the class described comprising a reel, automatic friction drive therefor, an adjusting means for said friction drive, manual adjusting means therefor, and ball bearings between said adjusting means and the reel.
11. A device of the class described comprising a reel, a friction drive therefor, a pivoted lever for adjusting said friction drive, and a movable cam for operating said pivoted lever.
12. A device of the class described comprising a reel, a friction drive therefor, a cam-operated lever for adjusting said friction drive, and an anti-friction bearing between said lever and the friction drive.
13. The combination with a rotatable reel having a friction disk secured thereto, of a driven friction disk adapted to engage the friction disk on the reel, and cam-controlled means for automatically varying the pressure of the driven friction disk against the friction disk on the reel.
14. In combination, a reel adapted to have a roll of flexible material wound thereon, a friction drive for said reel, a cam-controlled mechanism for adjusting the friction drive, and means contacting the roll of material on the reel for operating said cam mechanism.
15. A device of the class described comprising a shaft, a reel rotatable thereon, a roll of material on the reel, means for controlling the rotation of the reel in accordance with the size of the reel of material thereon, and a pivotally mounted cam operated mechanism for automatically adjusting said controlling means.
16. A device of the class described comprising a shaft, a reel rotatable thereon, means on the shaft for controlling the rotation of the reel, a pivoted lever for adjusting said means, and a movable cam for operating said pivoted lever.

In testimony whereof I have hereunto subscribed my name in the presence of two subscribing witnesses.

FRANK M. PIERCE.
